UNITED STATES PATENT OFFICE.

HOWARD G. ALLEN, OF NIAGARA FALLS, NEW YORK, ASSIGNOR TO MORRISON STITCHER CORPORATION, OF NIAGARA FALLS, NEW YORK, A CORPORATION OF NEW YORK.

STAPLING MACHINE.

Application filed January 2, 1926. Serial No. 78,746.

This invention relates to a stapling machine or wire stitcher and more particularly to a machine for staying or connecting the walls of a box at the corners thereof by means of wire stitches or staples.

It is one of the objects of this invention to produce a stapling machine of this character designed primarily as a corner stayer for boxes which will take ordinary flat or round wire and convert the successive sections of the same into U-form, then bends the same so that the legs of the staple converge downwardly and the cross bar of the same is arched upwardly, then forces the legs through the walls of a box adjacent to a corner thereof, and then presses the cross bar of the staple in the form of an angle against the outer corner of the box and presses the legs against the inner side of the walls and draws the staple and the walls firmly together to produce a strong and durable box corner. A further object of this invention is to accomplish this result by means which are comparatively simple in construction, reliable in operation, and capable of working efficiently for a long time without wearing unduly nor requiring frequent replacement, or repairing.

In the accompanying drawings:

Figure 1 is a fragmentary side elevation, partly in section of a stapling machine embodying my improvements, the sectional part being taken on line 1—1, Figure 2.

Figure 2 is a vertical longitudinal section of the same, taken on line 2—2, Figure 1.

Figure 3 is a horizontal section taken on line 3—3, Fig. 10.

Figure 4 is a vertical cross section, on an enlarged scale, taken on line 4—4, Figure 1, and showing the parts in the same position.

Figure 5 is a side view of the parts in same position as Figure 4.

Figure 6 is a vertical longitudinal section taken on line 6—6, Figure 4, being the lower part only of the mechanism.

Figure 7 is a front view of the working parts similar to Figure 4 but slightly later in the cycle of machine operation.

Figure 8 is a front view similar to Figures 4 and 7 but showing the parts in still another position and still later in the cycle of operations.

Figure 9 is a fragmentary front elevation,

similar to Figure 8, but later in the cycle of operations and showing the clinching mechanism in section.

Figure 10 is a fragmentary side view partly in section, similar to Figure 9, taken on line 10—10, Fig. 9.

Figure 11 is a vertical longitudinal section similar to Figure 9 but showing the completion of the staple driving and clinching operation.

Figure 12 is a vertical longitudinal section taken on line 12—12, Figure 11.

Figure 13 is a transverse section taken on line 13—13, Figure 1 looking forwardly.

Figure 14 is a fragmentary perspective view of the lower or stapling forming, guiding and driving portion of the head of the machine.

Figures 15 to 19 are perspective views showing the different forms the piece of wire of each staple assumes during the operation of forming and applying the same to a box corner.

Figure 20 is a perspective view showing the manner of applying the staple to a box in which the walls overlap each other at the corner between the same.

Figure 21 is a cross section of the corner of a box showing the manner of applying a staple thereto when the walls thereof merely abut at the corner.

Figure 22 is a cross section on line 22—22, Figure 1.

Figure 23 is a fragmentary perspective view of the head of the stapling machine showing the same modified for use in making staples of round wire.

Figure 24 is a perspective view of a ribbon wire staple driver.

Figure 25 is a perspective view of the staple forming block.

Figure 26 is a horizontal section taken on line 26—26, Figure 12.

Similar characters of reference indicate like parts throughout the several views.

In its general organization this machine comprises means for feeding the wire from which the staples are produced, means for cutting the wire successively into lengths suitable for forming staples, means for preliminarily forming the staples of U-form, and supplemental means for additionally forming the staples and guiding and driving the same through the corners of boxes and at

taching the same thereto. The wire feeding and cutting and the preliminary forming mechanism may be variously constructed and is not a part of the present invention, 5 the novelty of the latter being confined to the supplemental means for additionally forming the staples, guiding the same and applying them to the box corners as will hereinafter more fully appear.

10 That portion of the main frame or body of the machine shown in the drawings comprises a rear standard or upright 30, a lower arm 31 projecting forwardly from the lower part of the standard and an upper arm 32 15 projecting forwardly from the upper part of the same. Upon the front part of the lower frame arm is arranged the means for supporting the boxes 33 of rectangular form which are intended to be stapled at the corners and on this end of this arm is also arranged the mechanism for clinching the staples on the corners of the boxes. On the front end of the upper frame arm is arranged the supporting head 34 upon which 20 is mounted the mechanism for feeding the staple wire, the cutter for severing the same into lengths, the means for effecting the preliminary and supplemental formation of the staples, and the means for guiding and 25 driving the same through the box corners for staying the same. The upper side 35 of the lower frame arm is of upwardly projecting V-shape form to form a saddle of this shape upon which the corner of the box is supported while the walls thereof are being stapled or stitched together at the upper corner. 30 This lower frame arm is preferably so mounted on the standard that the front end of the same is capable of being raised and lowered for adapting the machine for stitching boxes which vary in thickness. As shown in Figure 1 of the drawings this is accomplished by connecting the rear end of the lower frame arm with the standard by a 35 horizontal transverse pivot pin 36 and a horizontal longitudinal adjusting screw 37 arranged in a lug 38 depending from the rear part of the lower frame arm and engaging the adjacent part of the standard so that by turning this screw in one direction or the other the front end of the lower frame arm will be moved vertically toward and from the head of the upper frame arm.

The numeral 39 represents the horizontal 40 driving shaft of this machine which is journaled lengthwise in the upper frame arm and adapted to be connected with and disconnected from a driving wheel 40 at its rear end by means of a clutch 28. The latter 45 may be of any suitable construction and the driving wheel may receive motion from any available source.

The wire 41 from which the staples are made is supplied from a roll 42 wound on a 50 spool 43 which is mounted in any suitable

manner on the top of the supporting head. From this roll the wire passes downwardly through a guide composed of upper and lower sections 44, 45 to the cutter mechanism which severs the same into lengths. These 70 guide sections are mounted on the supporting head and the wire is moved intermittently through the same by means of a feed mechanism having feed rollers 46, 47 engaging with opposite sides of the wire between the upper and lower guide sections and rotated step by step in any suitable manner, for instance, by the means shown in Letters Patent of the United States No. 644,754 granted March 6, 1900 to M. V. Allen 80 to which reference may be made for a complete description of this wire feed mechanism.

The cutter mechanism may be of various forms but generally the same may also be similar to that shown and described in the above mentioned Letters Patent, the same consisting essentially of a fixed tubular blade 48 which is mounted on a block 49 on the lower part of the front side of the supporting head and receiving the wire, and a movable blade 50 adapted to cooperate with the fixed blade for severing the wire at suitable intervals and actuated in any approved manner.

As the wire advances from the cutter mechanism the same passes through a rearwardly opening mouth or slot 51 in the lower arm of an anvil lever 56 and over an anvil 53 on this lever which forms the lower side 100 of this slot. This anvil lever is pivoted by a horizontal transverse pin 54 to the block 49. After the wire has been advanced a length through the feed slot of the anvil lever and before the same is cut off from the supply 105 wire the same is gripped by clamping the same between the anvil and an upper gripper jaw or finger 57 engaging the top of the wire, as shown in Figure 6. This gripper jaw projects rearwardly from the lower part of an upright gripper rod 58 which slides in a guideway on the anvil lever and is yieldingly held in its depressed or closed position by a spring 59 arranged in a pocket 60 in the anvil lever and engaging its upper end with 110 a pin in the top of this pocket and its lower end with a pin 61 on the gripper rod. The raising of the gripper rod is effected by a gripper lever or crank 62 of elbow form which is pivoted on the supporting block 49 and has a horizontal arm pivotally connected with the upper part of said gripper rod, as shown in Fig. 1, and an upright arm which is actuated by motion derived from a vertically movable forming slide or bar 63 guided on 115 the supporting head of the frame, as shown in Fig. 7. For this purpose this forming slide is provided on its front side with a cam face having an upper vertical portion 64 and a lower inclined portion 65 which are adapt- 120

ed to engage with a roller 66 on the upright arm of the gripper lever so as to open and close the wire gripper. The forming slide is raised and lowered by means of a roller 5 67 on the rear side of the same engaging with a groove cam 68 on the front side of a driving disk 69 secured to the front end of the driving shaft 39.

On its front side this forming slide is provided with an upright guideway 70 in which a driving bar 71 slides vertically and on opposite sides of the lower part of this guideway the forming slide is provided with two upright forming jaws 72, 72, the opposing 10 faces of which are parallel and provided with upright grooves 73. The driving bar is reciprocated vertically by means of a link 74 pivotally connected at one end by a pin 75 with the upper end of the driving bar and 15 pivotally connected at its other end with a crank pin or wrist 76 on the front side of the driving disk 69, as shown in Figures 1, 4, 5 and 8.

On the lower part of the front side of the 20 driving bar is mounted a driver 77 which is provided on its opposite vertical edges with ribs 78 engaging with the grooves 73 in the forming jaws and at its lower end this driver is provided with two square bearing faces 25 131 and a V-shaped bearing face 79 which are adapted to engage with the cross bar 80 of the staple and bend the same into V-form while driving its legs 81 through the work 30 piece and pressing this cross bar to the angular corner of the box which is being stayed while supported on the V-shaped saddle of the machine. In Figure 24 is shown a rearward view of the driver. It should be noted that the V-shaped bearing faces do not extend to intersect the ribs 78. At each side of the lower end of the driver are two flat faces 131 square with the ribs and into which the V-shaped faces merge. The width from front to back of these faces 131 is slightly 35 less than the width from front to back of ribs 78. In front of these faces are downwardly projecting horns 132 whose rearward faces incline forwardly slightly in a downward direction.

50 Mounted on the lower end of the forming slide and movable horizontally and lengthwise into and out of the path of the driver is a staple supporting shoe 83. This shoe slides at its opposite longitudinal edges in guideways 84 on the lower end of the forming bar and the underside of this shoe together with the lower end of the forming bar are constructed to form a V-shaped recess 85 whereby the same are adapted to fit over and 55 engage with the V-shaped corner of a box which is supported while being stapled on the correspondingly shaped saddle of the lower arm of the main frame. On opposite sides of its front end this shoe is provided 60 with two horns 86 which are adapted in the

forward position of the shoe to project underneath the forming jaws and on their upper sides these horns are provided with concave curved surfaces 87 which in the forwardly projected position of the shoe are arranged below the grooves 73 of the former jaws. This shoe is retracted rearwardly from underneath the driver during the descent of the same with the driving bar by means of a cam 88 mounted on the lower 70 rear part of the driving bar and engaging with a cam face 89 on the upper front central part of the shoe. The latter is yieldingly held in its foremost position by spring pressure preferably derived by means shown in 75 Figures 1, 3, 5 and 10. This consists of a bracket 120 rigidly attached to the front part of the body 32 carrying a plunger 91 around which is a spring 90. This spring tends to force the plunger 91 forwardly until 80 it is stopped by pin 123 in its rearward end. The guideways 84 for turning the block 83 are in the lower end of the side pieces 126 rigidly attached to the lower end of former slide 63 and spaced apart by the block 125. 85 In the upper end of the space block 125 is a pin 124 over which loosely sets a bar 121 having fixed to it a cam block 122. This bar and attached cam are thus loosely hinged over pin 124 so that the lower end may always be in contact with the rearward end of the turning block 83. As the former slide 63 is drawn up by rotation of the cam 69 the condition shown in Figure 5 is presented, 90 that is, the plunger end 91 is below the cam 100 block 122 and so the turning block is free to be moved easily back to its rearmost position. The pressure of the spring 133 is transmitted to the anvil lever 56 by a pin 150 sliding in the lower part of the block 49, as 105 shown in Fig. 1. Further rotation of the cam 69 brings the former slide 63 downward and carries the cam 122 under the forward end of the plunger 91 and the condition shown in Figure 10 is arrived at. Here the 110 cam 88 on the lower rearward end of the drive bar has forced the block 83 rearwardly against the tension of the spring 90. It will be seen that the purpose of this scheme for 115 mounting the spring 90 is to put a yielding pressure against the back of the turning block 83, when the former slide 63 is in its lower position only. The forward movement of the turning block 83 under the action 120 springs 90 is limited by engagement of shoulders on the front end of this turning block with the lower part of the rear side of the forming jaws. On the lower right-hand side of the anvil lever 56 is an adjustable eccentric stud 52 mounted to co-operate with the cam block 127 on the right former 72 so as to swing the anvil lever 56 outward whenever the former slide 63 is downward. It is shown in this position in Figures 7, 8, 9 and 10. This is the position the anvil lever as- 125

sumes when taking wire from the feeding mechanism. As the former slide 63 moves upward an eccentric stud 52 moves off from the cam block 127 the anvil bar 56 would be forced rearward by the pressure of the spring 133 (see Figure 1) were it not that the cam 129 mounted on the plate 82 on the drive bar 71, co-operates with cam face 130 on rearward side of the anvil bar. This cam 10 bar 82 maintains the anvil bar 56 in its outward or frontward position until such time as the lower end of the bar 82 passes upward off of cam 130 on the anvil bar. The purpose of this auxiliary cam control of anvil bar 56 is to keep its lower end 53 from contact with the part 93 which lies directly back of the driver 77 and under these conditions projects below it.

After the staple blank is severed from the supply wire, the latter is carried rearwardly so that its central part is underneath the driver and the ends thereof underneath the former jaws, as in Figures 4, 5 and 6. The latter then descend and bend 25 the ends of the wire staple blank downwardly along opposite sides of the anvil in the form of legs at which time these legs are received by the grooves 73 in the former jaws, as shown in Figure 7. The forming 30 slide descends until the clamping faces 85 at its lower end rest on the box corner which is to be stapled and then the driving bar descends and first causes the U-shaped staple to be carried downwardly between the forming 35 jaws and then continued in their downward movement during which the lower ends of the staple legs are engaged with the curved surfaces 87 of the shoe horns whereby the staple legs are turned toward each 40 other and caused to converge downwardly and the cross bar of the same is caused to arch upwardly, as shown in Figure 9. During the last part of this downward movement of the driver the same forces the legs 45 of the staple downwardly through the walls of the box and presses the cross pieces against the outer side of this corner so that the same conforms to the angular shape of the box corner, as shown in Figure 11. During 50 this final downward movement of the driver the turning block is moved rearwardly so that its horns clear the path of the driver which retracting movement of the shoe is effected by engagement of the cam 55 88 on the driving bar with the cam face 89 on the shoe, as shown in Figures 10 and 12. The driver does not force the shoe backwardly thereby relieving the driver from undue wear.

As the shoe moves rearwardly the dragging effect of its horns on the lower ends of the staple legs might possibly dislocate them and interfere with the operation of properly driving the same through the box corner.

65 To avoid this a guard or shield 93 is pro-

vided which is mounted on the driving bar so as to be capable of moving vertically thereon between the rear side of the driver and the front side of the shoe retracting cam 88. A guideway 94 is provided for this 70 purpose on the lower part of the front side of the driving bar which guideway receives said shield. A spacing plate 95 is arranged between the rear side of the driver and the driving bar which plate is received by a 75 vertical slot 96 in the shield, as shown in Figures 1, 3, 6 and 12, thereby serving to limit the vertical movement of the shield on the driving bar and preventing displacement of the same. The shield is yieldingly held 80 in its downwardly projected position beyond the driver by means of a spring 97 arranged in a pocket 98 in the driving bar and engaging its lower end against said shield and its upper end against a pin 99 at the top 85 of said pocket, as shown in Figures 1, 6 and 12. The lower end of the shield is provided with a V-shaped notch 29 whereby the same is adapted to fit the angular corner which is being stapled. During the first 90 part of the descent of the driving bar the shield projects below the driver until the shield engages with the box corner during which time the driver is moving the U-shaped staple downwardly between the 95 forming jaws. After the shield engages the box the driver continues its downward movement independently of the shield and during this time the staple is carried downwardly and its legs are deflected toward each 100 other by engaging with the curved faces of the horns. At this time the latter are also withdrawn rearwardly by the cam 88 but the legs of the staple are prevented from following these horns but instead are held 105 in position by the shield and directed downwardly through the box while under the pressure of the driver from the top.

After the legs of the staple have been thus forced obliquely downwardly through 110 the box corner and the cross bar of the same has been pressed into angular form against the outer side of the box corner so as to conform therewith the lower ends of the staple legs are clinched toward each other 115 and against the underside of the box corner so as to complete the staying of the box corner. Various clinching mechanisms may be employed for this purpose that, for example, which is shown in the drawings being constructed as follows:

The numeral 100, Figure 1, represents a clincher box mounted on the front end of the lower arm of the main frame vertically in line with the driver and forming jaws. 125 On its inner side this clincher box is provided with a vertical guideway 101 in which a clincher 102 slides vertically. At its upper end this clincher is provided with a V-shaped face 103 which, upon raising the 130

- clincher, is adapted to engage with the staple legs and bend them toward each other and press the same against the inner angular side of the box corner, and thereby complete 5 the fastening together of the corner of the box, as shown in Figure 11. Although various means may be employed for raising and lowering the clincher it has been found satisfactory in practice to employ a vertically 10 swinging operating lever 104 arranged lengthwise underneath the lower work supporting arm of the main frame and having its front arm engaging with an opening 105 in the clincher, a pivot or stud 106 which 15 is mounted on the frame arm 31 and upon which the operating lever turns, a spring 107 interposed between the rear arm of the operating lever and said frame arm 31 and serving to turn this lever in the direction 20 for lowering the clincher in the clincher box, a vertically movable shifting bar 108 guided at its upper and lower ends of the frame standard and connected with the rear arm of the operating lever, and a cam 109 arranged 25 on the driving shaft and engaging with a roller 110 on the shifting bar for depressing the same and elevating the clincher into working position. The pivot 106 is preferably made adjustable so as to 30 enable the movement of the clincher to be adapted to the inner side of the box corner and staple. For this purpose the pivot is formed eccentrically on a trunnion 111 which is journaled in a bearing 112 on one 35 side of the frame arm 31 and is adapted to be turned by a screw driver applied to a nick 113 in the outer end of this trunnion, and a clamping screw 114 arranged in the opposite side of the frame arm 31 and engaging 40 the pivot or stud 106, as shown in Figure 25. By turning the trunnion the pivot 106 will be raised or lowered and the effect of this operating lever on the clincher changed accordingly.
- 45 In Figures 1 to 22 is shown a machine which is designed for use in operating on flat or ribbon wire but obviously the machine can be adapted for use on round wire as well, as shown in Figure 23. In these figures the opposing inner sides of the forming jaws 115 are provided with rounded grooves 116 and the lower end of the driver 117 is provided with a seat which is adapted to receive a blank 119 of round wire 50 preparatory to bending the same into the form of a staple and applying the same to the work piece.
- 55 The operation of the machine briefly is as follows:
- 60 A length of wire is first fed into the slot 51 in the lower end of the anvil lever by the wire feeding mechanism. During the period of feeding the wire the anvil 53 occupies the position shown in Figure 10. After the 65 wire has been fed forwardly an extent suffi-
- cient to form a cross bar equal to the width of the anvil and legs of the requisite length projecting equal distances from opposite sides of the anvil, then the staple blank is cut from the supply wire. Shortly before 70 the wire is cut off but after its forward feeding motion has stopped in the forward rotation of cam 68, the forming slide is raised and the roller 66 of the gripper lever 62 is caused to drop off the vertical 75 cam surface 64 and move toward the left side of the forming slide, as shown in Figure 4. This allows a counter-clockwise rotation of the gripper lever 62 and so permits the gripper finger to be 80 pressed firmly down on the wire by its spring. Thus, the wire when cut off will be firmly secured in the slot in the lower end of the anvil lever and centrally located therein.
- 85 The continued clockwise motion of the cam 68 causes the driving bar to rise together with the forming slide until the same reach the position shown in Figures 1, 2, 4, 5 and 6. During the last part of the 90 upward movement of the driving bar the cam bar 129 on the front side of the same is moved upwardly under the cam 130 on the rearward side of the anvil lever. This allows the anvil lever under influence of 95 spring 133 to move the wire blank on its lower arm under the lower end of the forming bar so that the opposite ends of the wire blank are directly in the path of the grooves or channels in the forming jaws, as shown 100 in Figures 4, 5 and 6. Further rotation of the cam 68 moves the forming bar or slide past the wire blank slot in the lower end of the anvil lever, thereby bending over the wire held thereby into the form of an inverted U with square corners, as shown in Figure 7. Shortly after the wire has been bent the cam face 65 of the forming slide 105 engages with the roller 66 on the gripper lever causing the gripper jaw to be raised 110 from the wire blank. Further motion of the cam 68 causes the former slide to descend and bring the cam 127 in contact with the stud 52 on side of anvil bar 56. Further downward motion of the driver brings it in 115 contact with the top of the staple as it lays in the grooves in the former jaws, as shown in Figure 8. The wire now bent into the form of a U-shape is driven downward by the flat faces 131 on the driver at the extremities of its central V-shaped recess, as 120 shown in Figure 8. Continued downward motion of the staple and driver brings them into the position shown in Figure 9, which represents the staple driven out of channels in the forming jaws and the legs of the same are driven against the turning surfaces 87 so that the staple is bent to the form shown in this figure and in which the legs converge 125 downwardly and the cross bar is arched up-
- 130

wardly while the legs are partway through the box. It is to be noted that at this time the projecting horns 132 on the driver are arranged over the corners of the staple and that their inwardly beveled faces serve to wedge it between these horns and the stripper 93. This serves to hold the staple in the driving mechanism.

As the driver continues its descent the 10 shoe is pushed back to avoid pressure from the lower rear edge of the driver which is effected by the cam 88 on the driving bar engaging the cam 89 on the shoe or turning block. As the shoe moves back it would 15 draw the staple back with it and away from in under the driver were it not for the shield. This shield or stripper comes in contact with the curved surfaces 87 of the horns before the shoe starts its motion rearward. This 20 is possible because the shield is yieldingly held so that its front end precedes the driver. This condition is shown in Figures 1, 4, 6, 7, 8, 9 and 10. Since the shield lies directly back of the staple and in contact with it, 25 the staple is not displaced laterally by the rearward motion of the supporting shoe. During the last part of the downward motion of the driver the legs of the staple are forced through the walls of the box forming 30 the sides of the corner and the cross bar of the staple is bent into V-form against the outside of the corner. Thereafter the clincher is raised and the legs are bent upwardly against the inner side of the box 35 corner. The driving bar and forming slide and all attached parts are now raised and the clincher is depressed and the cycle of operations repeated as often as necessary.

The several forms which the wire assumes 40 during the operation of converting the same into a staple and applying it to a box corner are illustrated in Figures 15 to 19. As there shown, Figure 15 represents the straight blank of wire after it is cut from the supply 45 wire, Figure 16 shows the blank bent into the form of a U-staple, Figure 17 shows the legs of the staple bent toward each other and the cross bar of the same arched upwardly preparatory to being applied to a box corner, Figure 18 shows the position of the legs 50 and the form of the cross bar when the staple is applied to a box corner, and Figure 19 shows the shape of the staple when clinched on a box corner. The corners of boxes may 55 be connected by staples in the manner described when one wall is provided with a flap 28 which is overlapped at the corner by the other wall of the box, as shown in Figure 20 or the two walls of the box may abut 60 against each other at the corner, as shown in Figure 21. In the former case one leg of the staple passes through one ply of material and the other through two plies, while in the latter construction both legs pass 65 through single plies of material. It will

now be apparent that in this stapling machine the staple is first made of the usual U-shape and then its legs are bent inwardly or toward each other by means of bending dies or surfaces so that the legs enter the 70 stock at right angles thereto and are completely supported and guided by these surfaces until the legs have fully entered the stock which is very important in staying 75 the corners of boxes.

Owing to the fact that the supporting shoe is driven back by a separate cam on the driving bar large contact surfaces can be provided which make for greater durability 80 and also relieves the driver from the wear of this work thus ensuring long life for the same. The supporting shoe, driver and shield are vital parts of the machine but the same can be produced at low cost, and will stand much abuse without getting out of 85 order.

It is to be noted that in addition to acting as a die for bending the legs of the staple, the V-shaped underside of the same also serves as a jaw to pinch or clamp the work 90 piece or stock on the saddle and thus hold the same reliably in place during the subsequent operation of applying the staying staples to the corners thereof. Obviously this machine can operate on wires of various 95 cross sections, for example, flat, round or square, by merely changing those parts which cooperate with the wire to suit the shape of the same.

I claim as my invention:

1. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece and a supporting shoe movable horizontally into and out of the path of said driver and having bending surfaces adapted to be engaged by the legs of the staple for bending the same inwardly toward each other.

2. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on 110 opposite sides thereof, a driver for moving the staple downwardly between said forming jaws and forcing the legs of the same through a work piece, a supporting shoe 115 movable horizontally into and out of the 120 path of said driver and having bending surfaces adapted to be engaged by the legs of the staple for bending the same inwardly toward each other.

125

- path of said driver and having bending surfaces adapted to be engaged by the legs of the staple for bending the same inwardly toward each other, said shoe and driver having cooperating cam surfaces for moving the shoe out of the path of said driver, and means for yieldingly holding the shoe in the path of said driver.
3. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and spring supported means for yieldingly holding the shoe in the path of said driver.
4. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, and a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and means for yieldingly holding the shoe in the path of said driver, said means including a spring mounted on a stationary part of the machine.
5. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and means for yieldingly holding the shoe in the path of said driver, the forward movement of said shoe being limited by engagement with the rear side of said forming jaws.
6. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and a spring pressed lever which yieldingly supports said shoe while the latter is in the position for bending the legs of the staple toward each other and which does not yieldingly support the same while the legs of the staple are previously bent downward by the formers.
7. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and means for yieldingly holding the shoe in the path of said driver, said means including a spring mounted on a stationary part of the machine.
8. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, a supporting shoe movable horizontally into and out of the path of said driver and having bending surfaces adapted to be engaged by the legs of the staple for bending the same inwardly toward each other, said shoe and driver having cooperating cam surfaces for moving the shoe out of the path of said driver, and means for yieldingly holding the shoe in the path of said driver.

- jaws downwardly along opposite sides of said anvil and bending said blank so as to form a cross bar on the anvil and legs on opposite sides thereof, a driver for moving the 5 staple downwardly between said forming jaws and forcing the legs of the same through a work piece, a supporting shoe movable horizontally into and out of the path of said driver and having bending surfaces adapted to be engaged by the legs of the 10 staple for bending the same inwardly toward each other, said shoe and driver having cooperating cam surfaces for moving the shoe out of the path of said driver, means 15 for yieldingly holding the shoe in the path of said driver comprising a spring pressed lever engaging with the rear end of said shoe, and a shoe support on which said shoe is guided and attached to said forming jaws.
- 20 9. A stapling machine comprising a forming bar provided with two forming jaws, an anvil for moving a staple blank to and supporting the same in the path of said forming jaws, means for moving said forming 25 jaws downwardly along opposite sides of said anvil and bending said blank so as to form a cross bar on the anvil and legs on opposite sides thereof, a driver for moving the staple downwardly between said forming 30 jaws and forcing the legs of the same through a work piece, a supporting shoe movable horizontally into and out of the path of said driver and having bending surfaces adapted to be engaged by the legs of the 35 staple for bending the same inwardly toward each other, said shoe and driver having cooperating cam surfaces for moving the shoe out of the path of said driver, means for yieldingly holding the shoe in the path of 40 said driver comprising a spring pressed lever engaging with the rear end of said shoe, a shoe support on which said shoe is guided and attached to said forming jaws, and clinching mechanism having a support, said shoe support and clinching mechanism support being shaped to clamp the work being stitched between them.
- 45 10. A stapling machine comprising a forming bar provided with two forming jaws, an anvil for moving a staple blank to and supporting the same in the path of said forming jaws, means for moving said forming jaws downwardly along opposite sides of said anvil and bending said blank so as 50 to form a cross bar on the anvil and legs on opposite sides thereof, a driver for moving the staple downwardly between said forming jaws and forcing the legs of the same through a work piece, bending means for 55 bending the legs of the staple toward each other comprising a horizontally movable shoe having two horns adapted to project forwardly across the path of the staple legs and having their upper sides provided with 60 concave curved surfaces which are engaged by 65 the legs of the staple as the latter is pushed downwardly by the driver.
- by the legs of the staple as the latter is pushed downwardly by the driver.
11. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having two horns adapted to project forwardly across the path of the staple legs and having their upper sides provided with concave curved surfaces which are engaged by the legs of the staple as the latter is pushed downwardly by the driver, the underside of said shoe being provided with a V-shaped recess.
12. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having two horns adapted to project forwardly across the path of the staple legs and having their upper sides provided with concave curved surfaces which are engaged by the legs of the staple as the latter is pushed downwardly by the driver, the underside of said shoe being provided with a V-shaped recess.
13. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having two horns adapted to project forwardly across the path of the staple legs and having their upper sides provided with concave curved surfaces which are engaged by the legs of the staple as the latter is pushed downwardly by the driver, the underside of said shoe being provided with a V-shaped recess.

of said driver having a V-shaped notch and flat horizontal surfaces on opposite edges of said notch, and horns arranged on the lower end of said driver in front of said horizontal surfaces.

14. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staples downwardly between said forming jaws and forcing the legs of the same through a work piece, bending means for bending the legs of the staple toward each other comprising a horizontally movable shoe having two horns adapted to project forwardly across the path of the staple legs and having their upper sides provided with concave curved surfaces which are engaged by the legs of the staple as the latter is pushed downwardly by the driver, the lower end of said driver having a V-shaped notch and flat horizontal surfaces on opposite edges of said notch, horns arranged on the lower end of said driver in front of said horizontal surfaces and means for holding the wire staple against said horizontal surfaces and in said notch.

15. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontal movable shoe having two horns adapted to project forwardly across the path of the staple legs and having their upper sides provided with concave curved surfaces which are engaged by the legs of the staple as the latter is pushed downwardly by the driver, the lower end of said driver having a V-shaped notch and flat horizontal surfaces on opposite edges of said notch, and horns arranged on the lower end of said driver in front of said horizontal surfaces, means for holding the wire staple against said horizontal surfaces and in said notch and a shield or stripper arranged in rear of said driver.

16. A stapling machine comprising a forming bar provided with two forming jaws, an anvil for moving a staple blank to and supporting the same in the path of said forming jaws, means for moving said form-

ing jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having two horns adapted to project forwardly across the path of the staple legs and having their upper sides provided with concave curved surfaces which are engaged by the legs of the staple as the latter is pushed downwardly by the driver, the lower end of said driver having a notch and the underside of said shoe having a recess, said notch and recess being of V-shape.

17. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having bending surfaces adapted to be engaged by the legs of the staple, means for retracting the shoe out of the path of the staple, and a shield adapted to engage the rear side of the staple and to hold the latter in place while the shoe is being disengaged therefrom.

18. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having bending surfaces adapted to be engaged by the legs of the staple, means for retracting the shoe out of the path of the staple, a shield adapted to engage the rear side of the staple and to hold the latter in place while the shoe is being disengaged therefrom and means for mounting said shield on said driving bar.

19. A stapling machine comprising a forming bar provided with two forming jaws, an anvil for moving a staple blank to and supporting the same in the path of said forming jaws, means for moving said form-

- ing jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having bending surfaces adapted to be engaged by the legs of the staple, means for retracting the shoe out of the path of the staple, a shield adapted to engage the rear side of the staple and to hold the latter in place while the shoe is being disengaged therefrom and means for mounting said shield on said driving bar comprising a spacing plate which is arranged between said driver and driving bar, said shield being provided with a vertical slot which receives said spacing plate. 70

22. A stapling machine comprising a forming bar provided with two forming jaws, an anvil for moving a staple blank to and supporting the same in the path of said forming jaws, means for moving said forming jaws downwardly along opposite sides of said anvil and bending said blank so as to form a cross bar on the anvil and legs on opposite sides thereof, a driver for moving the staple downwardly between said forming jaws and forcing the legs of the same through a work piece, bending means for bending the legs of the staple toward each other comprising a horizontally movable shoe having bending surfaces adapted to be engaged by the legs of the staple, means for retracting the shoe out of the path of the staple, and a shield adapted to engage the rear side of the staple and to hold the latter in place while the shoe is being disengaged therefrom and provided in its lower edge with a V-shaped notch. 80 85 90 95
- 20 25 30 35 40 45 50 55 60 65
23. A stapling machine comprising a forming bar provided with two forming jaws, a driver movable vertically between said jaws, means for moving a staple blank to and supporting the same in the path of said forming jaws comprising an anvil lever having an anvil upon which the blank is adapted to be supported, a gripper rod guided on the rear part of said lever and provided at its lower end with a gripper finger adapted to engage with the blank resting on said anvil and a sliding staple supporting shoe yieldingly mounted on the lower end of the forming bar. 100 105
- 20 25 30 35 40 45 50 55 60 65
24. A stapling machine comprising a forming bar provided with two forming jaws, a driver movable vertically between said jaws, and means for moving a staple blank to and supporting the same in the path of said forming jaws comprising an anvil lever having an anvil upon which the blank is adapted to be supported, a gripper rod guided on the rear part of said lever and provided at its lower end with a gripper finger adapted to engage with the blank resting on said anvil, and means for actuating said gripper rod comprising a spring mounted on the anvil lever and operating on the gripper rod to depress the same, an elbow lever having a fixed fulcrum which is arranged at right angles to the fulcrum of the anvil lever and which has a horizontal arm connected with said gripper rod, a cam arranged on said former bar and operating on the upright arm of said elbow lever for 110 115 120 125

turning the same in a direction for lifting the gripper rod during the descent of the forming bar, and a staple forming shoe movable horizontally and lengthwise into 5 and out of the path of the driver.

25. A stapling machine comprising a forming bar provided with two forming jaws, a driver movable vertically between said jaws, and means for moving a staple blank to and supporting the same in the path of said forming jaws comprising an anvil lever having an anvil upon which the blank is adapted to be supported, a gripper rod guided on the rear part of said lever and 10 provided at its lower end with a gripper finger adapted to engage with the blank resting on said anvil, said anvil lever being provided on its side with an adjustable projection, and a cam block which is mounted 15 on one of said forming jaws and which is adapted to be engaged by said projection for retracting said lever, and spring means 20 for holding the lever yieldingly from the time the same is in the staple forming position to the time it is in the wire feeding position.

26. A stapling machine comprising a forming bar provided with two forming

jaws, a driver movable vertically between said jaws, and means for moving a staple blank to and supporting the same in the path of said forming jaws comprising an anvil lever having an anvil upon which the blank is adapted to be supported, a gripper rod guided on the rear part of said lever 30 and provided at its lower end with a gripper finger adapted to engage with the blank resting on said anvil, said anvil lever being provided on its side with an adjustable projection, and a cam block which is mounted 35 on one of said forming jaws and which is adapted to be engaged by said projection for retracting said lever, and spring means 40 for holding the lever yieldingly from the time the same is in the staple forming position to the time it is in the wire feeding position and a shield arranged below the driver at the lower end of said driver bar, said anvil bar being provided on its rear side with a cam surface cooperating with 45 said cam block for holding the anvil bar in its forward position while wire is being fed to it and said driver bar is moved upward and prevented from coming in contact 50 with said shield.

HOWARD G. ALLEN.
